HENRY D. JAMES, OF EDGEWOOD PARK, PENNSYLVANIA, ASSIGNOR TO WESTINGHOUSE ELECTRIC & MANUFACTURING COMPANY, A CORPORATION OF PENNSYLVANIA.

CONTROL SYSTEM.

Application filed August 17, 1920. Serial No. 404,133.

My invention relates to systems of control and especially to the automatic protection of starting devices, such as resistors or transformers, that are employed for starting motors into operation.

One object of my invention is to provide a control system of the above-indicated character wherein, under certain operating conditions of the starting means, the machine circuit shall be interrupted or otherwise modified to thus protect the starting means from abnormal operating conditions, such as prolonged overload.

More specifically stated, one object of my invention is to provide a thermal relay device that is responsive to the temperature of a starting resistor or auto-starter coil for modifying the machine connections, that is either increasing the accelerating voltage applied to the machine or entirely interrupting the machine circuit.

Other objects of my invention will become evident from the following detailed description taken in conjunction with the accompanying drawings, wherein

Fig. 1 is a diagrammatic view of a direct-current system of control to which my present invention is applied;

Fig. 2 is a diagrammatic view of an alternating-current control system embodying one form of my invention;

Fig. 3 is a diagrammatic view of a modified form of the system that is shown in Fig. 1;

Fig. 4 is a sequence chart of well known form indicating the preferred order of operation of the switches that are employed in the systems of Fig. 2 and Fig. 5, and

Fig. 5 is a diagrammatic view of a modified form of alternating-current control system with which my present invention is incorporated.

Referring to Fig. 1 of the drawings, the system here shown comprises suitable supply circuit or line conductors $L+$ and $L-$, respectively, a direct-current shunt motor 4 having a commutator-type armature 5 and a shunt field winding 6, a starting or accelerating resistor 7 that is sub-divided into three portions 7a, 7b and 7c, a plurality of

resistor-short-circuiting switches or contactors 1, 2 and 3, a circuit-breaker or line switch 8, a starting or hand-operated switch 9, and my thermal relay or protective device 10.

The relay device or thermo-couple 10 may be of any suitable form and is here shown as comprising a pair of plates 14 and 15 of metals having materially different temperature coefficients of expansion, such as brass and steel, for example. The two metals are joined in intimate electrical contact in accordance with any well known method and are provided with a number of slots or longitudinal cuts, whereby two adjacent corners of the device may be employed as circuit terminals and a tortuous path for the electric current is provided. A contact strip or bar 16 is insulatedly secured to the under side of the bimetallic device and normally 70 bridges a pair of stationary contact members or terminals 17 and 18.

Whenever the temperature of the relay device 10 is below a predetermined limit which corresponds to an overload condition of the starting device 7, the relay occupies its illustrated lower position. However, when such abnormal conditions are reached, the thermal action of the current traversing the bimetallic relay element is sufficient 80 to cause it to bend concave upwardly and thus separate the bridging contact member 16 from the stationary contact terminals 17 and 18.

The terminals of the relay device 10 are connected to the respective ends of the resistor section 7c, which is the last section to be short-circuited or excluded from circuit during the motor acceleration. In this way, the maximum degree of protection is afforded to the starting resistor, since the greatest heating effect will occur in the resistor section 7c.

Assuming that it is desired to effect acceleration of the motor 4, the hand switch 9 may be closed to establish a circuit from the positive line conductor $L+$ through the switch 9, actuating coil of the line switch 8, stationary contact terminals 17 and 18, which are normally bridged by contact bar 100

16 of the relay device 10, and thence to the negative line conductor L-. The line switch 8 is thus closed to connect the starting resistor 7 and the motor 4 across the 5 supply circuit.

The resistor short-circuiting switches 1, 2 and 3 may then be successively closed in accordance with any well-known method for short-circuiting the sections 7a, 7b and 7c of 10 the starting resistor to effect a smooth acceleration of the motor 4.

If, at any time during such accelerating operation prior to the closure of the switch 3 and the consequent complete short-circuiting of the starting resistor 7, an overload current should traverse the starting resistor or, if the resistor is maintained in circuit beyond a certain interval, then the thermal relay device 10 is heated to such a temperature that the bimetallic element curls upwardly to effect separation of the contact member 16 from the terminals 17 and 18.

In this way, the actuating coil for the line switch 8 is de-energized to cause the line switch to open and thus disconnect the motor 4 from the supply circuit. The motor cannot be restarted until the relay device 10 has sufficiently cooled down to again bridge the stationary contact terminals 17 and 18, 20 at which time the starting resistor 7 will again be in safe operating condition.

In the system shown in Fig. 1, therefore, I employ a thermal relay device for interrupting the machine circuit under abnormal 35 conditions in the starting resistor. Fig. 2 shows a different application of the relay device wherein an accelerating switch is closed upon the operation of the relay device to continue the motor operation at a 40 higher speed.

The system shown in Fig. 2 comprises a three-phase supply circuit including line conductors L1, L2 and L3 for supplying energy to an induction motor 22 having a 45 primary winding 23 and a secondary winding or squirrel-cage rotor 24. An auto-transformer, having a plurality of coils 20 and 21, is initially interposed between the line conductors and the induction motor for 50 starting purposes, in accordance with a well-known practice. A voltage relay 25, a plurality of accelerating switches 11, 12 and 13, and a thermal relay device 26 are also employed for starting and accelerating the 55 induction motor 22.

The thermal relay device 26 comprises a movable bimetallic element having strips 27 and 28 of suitable metals as previously described, stationary contact members 29 and 30 being placed respectively above and below one end of the bimetallic element which normally, that is, under low-temperature conditions, makes contact with the stationary terminal 30. For the purpose of heat-

ing the relay device in accordance with the 65 time that current traverses the auto-transformer, a heating coil 26a is wound around the bimetallic element and is connected across the auto-transformer coil 20.

The switch or contactor 12 is shown as 70 being electrically operated and of the double-contact type, while switches 11 and 13 are provided with a triple set of contact members. Furthermore, to insure that switches 11 and 13 will not be concurrently 75 closed to effect improper connections of the auto-transformer to the supply circuit, an oscillatable bar or mechanical interlock 31 is located between the contactors, in accordance with a familiar practice. 80

Assuming that it is desired to effect acceleration of the induction motor 22, the hand switch 9 or its equivalent is closed to establish a circuit from the line conductor L3 through the switch 9, conductors 36 and 37, actuating coil of the switch or contactor 11, conductor 38, stationary terminal 30 and metallic strips 27 and 28 of the thermal relay device 26, and conductors 39 and 40 to a second line conductor L1. 85

In this way, the switch 11 is closed, thereby establishing another auxiliary circuit from the conductor 37 through movable contact member 41 of the contactor 11, conductor 42 and the actuating coil of the voltage relay 25 to conductor 40. The closure of the voltage relay establishes a holding circuit therefor from conductor 36 through movable contact member 43 of the relay and thence through the actuating coil to conductor 40, thus rendering the closure of the relay independent of subsequent opening of the contactor 11. 95

The closure of the contactor 11 establishes a main circuit from the line conductor L2 105 through auto-transformer coil 21, conductor 32, movable contact members 33 and 34 of the contactor 11 in its upper or closed position, conductor 35, auto-transformer coil 20, and thence through conductor 40 to the 110 line conductor L1.

The closure of the voltage relay 25 establishes another auxiliary circuit from conductor 36 through movable contact members 43 and 44, conductors 45 and 46, movable contact member 47 of the contactor 13 in its lower or normal position, conductor 48, actuating coil of the contactor 12 and conductor 49 to conductor 40. 115

In this way, the contactor 12 is closed to 120 establish one main circuit from an intermediate tap 50 on the auto-transformer coil 20 through conductor 51, movable contact member 52 of the contactor 12 in its upper or closed position, and conductors 53 and 125 54 to one primary phase-winding of the induction motor 22. Another main circuit is concurrently established from a correspond-

ing intermediate tap 55 on the auto-transformer coil 21 through conductor 56, movable contact member 57 of the contactor 12 and conductor 58 to a second primary phase-winding.

5 The remaining phase is completed from the line conductor L3 through conductor 59 to the third primary phase-winding of the induction motor.

10 The motor 22 is thus started into operation with a suitably low voltage impressed across the primary winding terminals thereof by reason of the inter-position of the auto-transformer, in accordance with a customary practice. The operation of the motor from the intermediate transformer taps continues until a balanced condition is reached, at which time the heating effect of the coil 26a on the thermal relay device 26 is sufficient to cause the bimetallic element of the relay device to bend concave upwardly and thus effect electrical contact between the bimetallic element and the stationary contact terminal 29.

25 Under this condition, a new circuit is established from conductor 40 through conductor 39, a bimetallic element of the relay device, stationary contact terminal 29, conductor 60, actuating coil of the contactor 13, and conductor 61 to conductor 45, whence circuit is completed through the voltage relay 25 to line conductor L3, as previously traced.

The closure of the contactor 13 causes the 35 opening of both of the contactors 11 and 12, as indicated by the sequence chart, Fig. 4. The contactor 11 is opened by reason of the mechanical interlocking through the bar 31 while the contactor 12 is opened by reason 40 of the de-energization of its actuating coil when the movable contact member 47 of the contactor 13 occupies its upper position.

Upon the closure of the contactor 13, one 45 main circuit is established from the line conductor L1 through movable contact member 62 of the contactor 13 and conductors 63 and 54 to one primary phase-winding of the induction motor. A second main circuit is completed from the line conductor L2 through conductor 64, movable contact member 65 of the contactor 13 and conductors 66 and 58 to a second primary phase-winding. The third phase-winding circuit is completed, as already traced, from the remaining 55 line conductor L3.

In this way, the full line voltage is impressed upon the primary winding terminals of the induction motor 22.

Fig. 3 shows a modification of the direct-60 current control system that was described in connection with Fig. 1 and comprises the motor 4, the starting resistor 7, the accelerating switches 1, 2 and 3, the line switch 8, and the hand switch 9, as previously described. In addition, a thermal relay device

70 is provided for protecting the starting resistor 7 and comprises a pair of thermally different metallic members 71 and 72 which normally occupy the illustrated position to bridge a pair of stationary contact terminals 73 and 74. A heating coil 75 is wound around the bimetallic element of the relay device and is connected across the resistor section 7c which, as described in connection with Fig. 1, is the last section to be 75 removed from circuit during the acceleration.

The starting and accelerating operation of the system is the same as that described for Fig. 1, and, likewise, the circuit of the line 80 switch will be opened if the thermal relay device 70 operates by reason of overload or undue heating during the motor acceleration, that is, prior to the closure of the last resistor short-circuiting switch 3.

85 However, to prevent the possibility of undesired action of the relay device for any reason after the closure of the switch 3, and, also, to prevent undue heating of the device, it is excluded from circuit as soon as the 90 switch 3 is closed by reason of a movable contact member 76 thereof being connected across the relay device contact terminals 73 and 74.

95 Referring to Fig. 5, the system here shown comprises a cam-operated type of controller in connection with an auto-transformer embodying coils 20 and 21 and an induction motor 22, my thermal relay device 26 being employed for a purpose similar to that set 100 forth in connection with Fig. 2.

The cam-operated controller may comprise a rotatable shaft 80 to which are rigidly secured a plurality of suitably configured cams 81 to 86, inclusive, for closing the 105 switches 11 and 11', 12 and 12' and 13 and 13' in the sequence that is indicated in Fig. 4.

A suitable ratchet clutch device 87, having 110 an operating magnet 87a for advancing the controller one step whenever the coil is energized, may be provided, although a pilot motor or any other equivalent mechanism may be employed, if desired.

An auxiliary or interlocking drum controller 88 is secured to one end of the operating shaft 80 for control purposes to be set forth. In addition, a "start" push-button or electrically-operated contactor 89 and a 115 "stop" device 90 of a similar character are 120 provided.

Assuming that it is desired to start the induction motor 22, the "start" button 89 is depressed to close an auxiliary circuit and simultaneously open the "stop" button by reason of the illustrated mechanical interlocking between the two buttons, in accordance with a familiar practice.

125 A circuit is thereby established from the line conductor L2 through conductor 91,

operating magnet 87a of the ratchet clutch 87, conductor 92, control fingers 93 and 94, which are bridged by contact segment 95 of the auxiliary drum 88, whence circuit is continued through conductor 96, push-button 89, conductor 97, stationary contact terminal 30 and metallic strips 27 and 28 of the thermal relay device 26, to the line conductor L3.

full speed, corresponding to the normal line voltage.

To return the cam controller to its illustrated initial position, the "stop" button 90 may be depressed to establish a circuit from the line conductor L3 through conductor 99, "stop" button 90, conductor 100, contact segment 95 of the auxiliary drum 88 in its position *c*, control finger 93 and thence through the operating magnet 87a, as previously traced. The controller is thus actuated, in the same direction as before, into the initial position *a*, wherein the connection just traced through the operating magnet 87a is interrupted. 70 75

It will be understood that whereas, in many cases, the time-element of the thermal device is less than that of the starting means, to thus provide adequate protection therefor, in other cases it may be desirable to design the device in such manner as to provide a time-temperature characteristic similar to that of the starting means. It is thus possible to provide a thermal device, the time-temperature characteristic of which bears any desired ratio to that of the starting means. 80 85 90

It will be seen that I have thus provided means dependent upon, or responsive to, the current, voltage or temperature conditions of 95 a motor-starting means, such as a resistor or a transformer coil, for either interrupting the machine circuit or effecting a further step of control when conditions are suitable. It will be understood that my invention is 100 not necessarily limited to the use of thermal relay devices, since other time-element mechanisms, to which broad class my thermal relay devices belong, may be utilized, if desired. Such other mechanisms may comprise, for example, dash-pots or clock mechanisms. 105

Furthermore, a thermal salt solution, such as that set forth in my copending application, Serial No. 394,563, filed July 7, 1920, may be utilized in place of the illustrated thermal devices. It will also be understood that my invention may be employed in connection with signal devices, such as lamps or bells, such devices being used either in lieu of, or in addition to the arrangements that I have illustrated. 115

Consequently, I do not wish to be restricted to the specific structural details, circuit connections or arrangement of parts herein set forth, as various modifications thereof may be effected without departing from the spirit and scope of my invention. I desire, therefore, that only such limitations shall be imposed as are indicated in the appended claims. 120 125

I claim as my invention:

1. In a control system, the combination with a dynamo-electric machine and a starting resistor in circuit therewith, of thermal 120

means connected in shunt relation to said resistor, and means for short-circuiting both the resistor and the thermal means.

2. In a control system, the combination
5 with a dynamo-electric machine and a starting resistor in circuit therewith, of thermal means having a winding connected in shunt relation to said resistor, and means actuated by said thermal means for short-circuiting

10 said resistor and said winding.

3. In a control system, the combination

with a dynamo-electric machine and a starting resistor in circuit therewith, of thermal means connected to be energized in accordance with the heating of said resistor,¹⁵ and means actuated by said thermal means for short-circuiting said resistor.

In testimony whereof, I have hereunto subscribed my name this 11th day of August 1920.

HENRY D. JAMES.
